Primary Examiner — Michael A. Pratt

(57) **CLAIM**

The ornamental design for a shoe, as shown and described.

DESCRIPTION

1. Shoe

- 1.1 : Perspective
1.2 : Front
1.3 : Back
1.4 : Right
1.5 : Left
1.6 : Top
1.7 : Bottom

The various views show a first embodiment of the shoe which is a right shoe; a second embodiment of the shoe is a left shoe and is a mirror image of the right shoe.
